UNITED STATES PATENT OFFICE.

ALEXANDER BACKHAUS, OF KÖNIGSBERG, GERMANY.

BOTTLE-STOPPER.

SPECIFICATION forming part of Letters Patent No. 601,698, dated April 5, 1898.

Application filed December 30, 1897. Serial No. 664,654. (No model.)

To all whom it may concern:

Be it known that I, ALEXANDER BACKHAUS, doctor of philosophy and professor of agriculture, a subject of the Grand Duke of Hesse, 5 residing at Königsberg, in the Province and Kingdom of Prussia, German Empire, have invented a new and useful Bottle-Stopper, of which the following is a specification.

The present invention relates to the air-tight closure of bottles and other receptacles for containing sterilized materials, particularly to bottles for sterilized milk, by means of an elastic cap slipped over the opening or mouth of the receptacle or bottle previous to the sterilizing operation and retained in position by means of its inwardly-thickened edge catching under a shoulder arranged around said opening, such as the usual bead of the bottle-neck. With stoppers of this description 10 the opening for allowing the vapors to escape during the sterilizing operation is provided for in the cap either in that portion of it which closes upon the bead or in the center and then is combined with a valve-like self-closing device. Obviously such opening has the effect of weakening the cap and making it accessible to damages. On the other hand, the combination with the said self-closing device complicates the manufacture and renders it costly. 15

My aim is to do away with the defects referred to by means of the present invention, which to this end consists in providing the lower part of said shoulder or swelling with a recess or depression which extends down to the lower edge of that portion and arranging below said edge and adjoining the same a rib-like projection or ledge at either side of the end of said depression, so as to produce 20 a small groove or channel. When the cap is slipped over the bead, it closes upon the latter in an air-tight manner; but as it rests with the respective portion of its inwardly-thickened edge upon the said ledges it allows 25 the channel formed by the latter, and consequently the depression in the bead, to remain in open communication with the atmosphere. If now the bottle or other receptacle is heated for sterilizing its contents, the vapors evolved, 30 in expanding the cap, lift the latter from the upper portion of the bead or shoulder until the depression is arrived at, when they es-

cape through the said channel into the atmosphere. Upon cooling the bottle or other receptacle the cap contracts again and hermetically closes upon the bead or shoulder, 55 so that the communication between the interior of the receptacle and the channel is perfectly broken.

On the annexed sheet of drawings I have 60 illustrated my invention as applied to a glass bottle for sterilized milk.

Figure 1 is an elevation of the bottle having the cap slipped over its bead, the lower ends of the channel-forming ledges being 65 visible. Fig. 2 is an elevation of the mouth portion of the bottle-neck, with the cap removed, so as to show the depression in the bead and the ledges. Fig. 3 is a central vertical section through the cap removed from 70 the bottle. Figs. 4 and 5 are vertical central sections according to line 4-5, Fig. 1, Fig. 4 showing the cap in its normal stopping position and Fig. 5 showing the cap lifted off from the bead, as during the sterilizing process. 75

a is the bead of the bottle-neck. In the lower portion of same is a small depression *a'*, originating at some distance from its lower edge and extending down to the latter. At each side of this depression the neck is provided with a small downwardly-directed ledge *a''*, parting from the bead, so that a channel *a'''* is produced, forming a downward prolongation of depression *a'*. 80

b is the stopping-cap, having the inwardly-thickened edge *b'*. 85

When the cap *b* is slipped over the bead *a*, its edge *b'* catches under the bead all around, with the exception of that portion which comes against the ledges *a''*, and consequently takes 90 its seat upon the latter, leaving the channel *a'''* and depression *a'* in free communication with the atmosphere, as illustrated by Fig. 4. Now when the filled bottle having the cap slipped over, as shown, is heated vapors are 95 generated, and these cause the cap to expand, the latter being retained upon the bottle by the co-operation of its thickened edge *b'* with the under side of the bead, acting as an abutment. This expansion goes on until the portion of the cap which is lifted off extends beyond the origin of depression *a'*, when the vapors escape through the same and the channel *a'''* into the atmosphere, as illustrated by 100

Fig. 5, where the passage of the vapors is indicated by arrows. If after sterilizing the bottle is allowed to cool, the evolution of vapors ceases and the cap contracts again, assuming the stopping position shown in Fig. 4.

The invention is applicable with the same effect to any kind of receptacle or vessel, provided the opening or mouth of the same be surrounded by a bead like that of bottles or 10 an annular shoulder.

I claim as my invention—

The combination with a receptacle having a shoulder around its opening, and an elastic stopping - cap provided with an inwardly- 15 thickened edge to catch under said shoulder,

of a depression formed in said shoulder and extended projections so arranged on the portion of the receptacle adjacent to its shoulder that a channel is formed for establishing communication between said depression and the atmosphere, substantially as and for the purpose stated. 20

In testimony whereof I have hereunto set my hand in the presence of two subscribing witnesses.

ALEXANDER BACKHAUS.
